UNITED STATES PATENT OFFICE

165,710

PATIO TABLE

Ray E. Currie and Hilbart F. Anderson, Oakland, Calif., assignors to Big Square Corporation, Oakland, Calif., a corporation of California

Application June 2, 1950, Serial No. 10,308

Term of patent 14 years

(Cl. D33—14)

To all whom it may concern:

Be it known, that we, Ray E. Currie and Hilbart F. Anderson, both citizens of the United States, residing at Oakland, in the county of Alameda, State of California, have invented a new, original, and ornamental Design for Patio Tables, of which the following is a specification, reference being had to the accompanying drawing, forming a part hereof.

We claim:

The ornamental design for a patio table, as shown.

RAY E. CURRIE
HILBART F. ANDERSON.
